WALLET

Herbert S. Chase, Woodmere, N.Y., assignor to Bernard Cahn Co., Inc., New York, N.Y.

Application November 28, 1958, Serial No. 53,569

Term of patent 7 years

(Cl. D87—3)

The characteristic features of my design reside in the portions shown in solid lines on the drawing.

I claim:

The ornamental design for a wallet, substantially as shown and described.
